UNITED STATES PATENT OFFICE.

JEREMIAH L. MAHONEY, OF NEW HAVEN, CONNECTICUT.

MACHINE FOR FORMING ROLLS ON RUBBER NIPPLES.

1,154,191.

Specification of Letters Patent. Patented Sept. 21, 1915.

Application filed October 14, 1914. Serial No. 866,570.

To all whom it may concern:

Be it known that I, JEREMIAH L. MAHONEY, a citizen of the United States, residing at New Haven, county of New Haven, State of Connecticut, have invented an Improvement in Machines for Forming Rolls on Rubber Nipples, of which the following is a specification.

This invention relates to machines for forming rolls or beads at the edges of the open ends of nursing bottle nipples, medicine dropper bulbs, finger cots, and similar articles composed of rubber or other plastic material. These rolls or beads have heretofore been formed by hand at a suitable period in the manufacture of the articles, said rolls or beads being made by turning the rubber or other material at the rough edge of the partly completed article, and rolling it outwardly away from the open mouth. This method is slow and expensive, and is also likely to result in a defective or uneven product.

The present invention has for its object to provide means whereby this work may be done mechanically in a rapid, economical, and accurate manner, thereby increasing the output and reducing the cost, and also resulting in a more perfect and even product.

With the foregoing and other objects in view I have devised the novel machine which I will now describe, reference being had to the accompanying drawings, in which:

Figure 1 is a plan view of a machine constructed in accordance with the invention. Fig. 2 is an end view thereof looking from the right in Fig. 1. Fig. 3 is a detail view of a portion of the forming roller and the bearings therefor. Fig. 4 is a detail view of one of the hollow forms used in the manufacture of nursing bottle nipples, showing a partly completed nipple in place thereon. Fig. 5 is a similar view showing the nipple after the formation of the roll or bead. Fig. 5a is a view similar to Fig. 2 showing the parts in different positions. Fig. 6 is a section taken substantially on line 6—6, Fig. 1 with the spool gear and the forming roller, together with the support for the latter, omitted. Fig. 7 is an end view of one of the chucks shown in Fig. 6. Fig. 8 is an enlarged longitudinal sectional view showing another form of chuck. Figs. 9 and 10 are views similar to Figs. 4 and 5 respectively, showing a solid form used in the manufacture of medicine dropper bulbs with one of

the bulbs in place thereon. Fig. 11 is a detail elevation of the mechanism for controlling the vertical movements of the forming roller. Fig. 12 is a section substantially on line 12—12, Fig. 6, showing the means for rotating the chucks. Fig. 13 is a detail front elevation of the cam plate for controlling the chucks to release the forms.

Referring to Fig. 1, 15 denotes the machine frame which may be of a suitable form and size to provide the necessary supports, bearings and guides for the various moving parts except as hereinafter pointed out. 16 denotes the power shaft journaled in the frame 15 and adapted to be rotated from any suitable source of power, as through a belt pulley 17 fast thereon. 18 denotes a bevel gear on the shaft 16 which meshes with a bevel gear 19 on a driving shaft 20 also suitably journaled in the frame 15. 21 (see Fig. 6) denotes a worm on the shaft 20 which meshes with a worm gear 22 on the spool shaft 23 also suitably journaled in the frame 15. 24 denotes the rotary form carrier or spool, the same comprising a cylindrical sleeve provided with annular end flanges 25 and 26. Said spool 24 is fixed to the spool shaft 23 by being clamped between a nut 27 and a washer 28 on the end of said shaft 20 and a sleeve 29 which abuts against a fixed collar 30 on said shaft. 31 denotes chucks or form holders which are journaled in bushings 32 having threaded engagement with tapped openings in the spool flanges 25 and 26. 33 denotes chuck operating rods which are slidably mounted in the chucks 31 and extend longitudinally thereof. Said rods are formed at their rearward ends with heads 34 and are normally held in their rearmost position, as shown at the top in Fig. 6, by means of springs 35 interposed between the heads 34 and internal shoulders within the chuck bodies. 37 (see Figs. 1, 6 and 13) denotes a cam plate suitably secured to the frame 15 and arranged transversely to the shaft 23 in the rear of the spool 24. Said plate is formed with an inclined or beveled upper edge arranged substantially in a horizontal plane passing through the axis of said shaft 23. The arrangement is such that, as the shaft 24 is rotated, the head 34 on the operating rod 33 of each chuck as it passes below the horizontal plane of the axis of the shaft 23 engages the inclined upper edge of the cam plate 37 and is forced forwardly thereby against the tension of the

corresponding spring 35 into the position shown at the bottom in Fig. 6. Also as each chuck moves upwardly in the rotation of the shaft 23 above the horizontal plane of the axis of said shaft the head 34 corresponding to said chuck is released by the plate 37 and the rod 33 moved rearwardly by its spring 35 into its normal position as shown at the top in Fig. 6.

10 The specific form of the chucks 31 may be in accordance with the class of articles to be operated upon, and the nature of the forms used for such articles. In Figs. 6 and 7 is shown a construction of chuck suitable for 15 use in connection with a hollow nipple form 36, such as is shown in Figs. 4 and 5. Said chuck comprises a suitable number (herein shown as three) of jaws 38 guided for movement in radial slots in the outer end of the 20 body of the chuck 31. Said jaws are radially movable in said slots, but are held against complete removal therefrom by means of an elastic band 39 surrounding said jaws and engaging notches 40 therein. The 25 jaws 38 are formed on their inner edges with cam surfaces 41 which coöperate with cam projections 42 on the operating rods 33. The arrangement of the parts is such that when the rod 33 is forced into its normal or 30 rearward position, shown at the top in Fig. 6, by its spring 35, engagement of the cam projections 42 with the cam surfaces 41 in the chuck jaws 38 causes said jaws to be thrown outwardly into a position to engage 35 the inner surface of the hollow form 36, thereby securely holding said form in position on the end of the chuck, as shown in Fig. 1. When, however, the rod 33 is forced forwardly by engagement of its head 34 40 with the cam plate 37, as shown at the bottom in Fig. 6, the cam projections 42 release the chuck jaws 38, permitting the elastic band 39 to draw the same inwardly, thereby releasing the form 36 and permitting 45 the same to be removed and replaced by another.

In Fig. 8 is shown a modified form of chuck suitable for holding solid forms, such as the form 360 shown in Figs. 9 and 10, 50 used in the manufacture of medicine dropper bulbs. Said chuck comprises a body 310, a sliding operating rod 330 having a head 340, and a spring 350, these parts being similar in construction, arrangement, 55 and function to the corresponding parts in the form of chuck last described. The body 310 is formed at its forward end with a preferably integral fixed jaw 43. 44 denotes a movable jaw having a shank 45 extending 60 through and guided in a suitable opening in the fixed jaw 43. 46 denotes pins carried by the shank 45 and engaging at opposite sides the inclined end of a cam slide 47 guided for longitudinal movement on the 65 chuck body 310 and secured to the forward

end of the rod 330. By this construction and arrangement of parts it will be seen that when the rod 330 is moved into its normal or rearward position by the spring 350, engagement of the upper face of the inclined 70 end of the cam slide 47 with the upper pin 46 will cause the movable jaw 44 to be drawn upwardly, thereby tightly clamping a form 360 inserted between the jaws against the fixed jaw 43. Forward movement of the 75 rod 330, or movement to the right as shown in Fig. 8, causes the cam slide 47, by engagement of the lower surface of its inclined end with the lower pin 46, to open the jaws and release the form held therebetween. 80

48 denotes pulleys on the chucks 31 between the bushings 32, said pulleys being secured to said chucks for rotation therewith in any suitable manner, as by set screws 49.

50 (see Fig. 12) denotes a belt extending 85 over the pulleys 48 and receiving power from any suitable source, preferably from a countershaft (not shown) at the base of the machine. As will be clear from Fig. 12, the arrangement is such that, in the rotation of 90 the spool 24, as each chuck 31 is brought above the shaft 23 the pulley 48 thereon will be engaged and rotated by the belt 50, and as said chuck is brought below the shaft 23 the pulley 48 thereof will be disengaged 95 from the belt 50, and at the same time the head 34 brought into engagement with the cam plate 37, so that friction of the parts serves to check the momentum of said chuck and stop the rotation thereof. The spool 24 100 and chucks 31 are rotated in the same direction, as indicated by the arrows on Figs. 1 and 2, the speed of rotation of said chucks, however, being greater than that of the spool. The pulleys 48, by engagement with 105 the ends of the bushings 32, serve also to hold the chucks 31 against longitudinal movement in said bushings.

Referring to Figs. 1 and 2, 51 denotes a short shaft journaled in the machine frame 110 15 and rotated by means of a pulley 52 which may be connected by a suitable belt (not shown) with a pulley 53 on the driving shaft 20. The shaft 51 is connected by means of a section of flexible shafting 54 115 with shaft 55 carrying a forming roller 56. The roller 56 is preferably composed of fiber for the reason that plastic or unvulcanized rubber will not stick to this material. The outer end of the shaft 55 is journaled in bearings 57 and 58 (see also Fig. 3) having squared outer surfaces. The bearing 57 is guided for vertical movement in a slot 59 in the downturned end of an arm 60 pivoted at 61 to the machine frame. By means of the arm 60 the roller 56 is held in a position transverse to the chucks 31, and forms 36 thereon, and above the same, so as to engage each of said forms as it approaches and passes its uppermost position in the rotation 125 130

of the spool 24. The roller 56 is disposed at a slight angle to the axes of the shaft 23, spool 24, and chucks 31, and consequently to the direction of movement of the forms, 5 the direction of inclination being in accordance with the direction of rotation of the spool 24, so that the point of initial engagement of the said roll with the forms is nearer the inner ends of said forms than the 10 point of final engagement of said parts, as will be clear from Fig. 1. The amount of said inclination may be adjusted by moving the arm 60 about its pivot 61, said arm being clamped in adjusted position by means of a clamp screw 62 having threaded engagement with a suitable part of the frame 15, and passing through a segmental slot 63 in the end of said arm beyond the pivot 61. The direction of rotation of the roller 56, 20 as indicated by the arrows on Figs. 1 and 2, is such that the movement of the side thereof which engages the forms 36 is outward with respect to said forms, or toward the body of the nipple or other article thereon. 25 The bearing 58 is received in a slot 64 (see Fig. 11) in a pivoted extension 65 of the upper arm of a bell-crank lever 66 pivoted at 67 to a bracket 68 bolted or otherwise secured to the frame 15. The extension 65 is pivoted at 69 to the body of the arm of the lever 66, and is held in adjusted position with respect to the body of said arm by means of a clamp screw 70 having threaded engagement with said extension 85 and passing through a segmental slot 71 in said body.

72 denotes a gear secured to the periphery of the flange 26 of the spool 24, said gear meshing with a pinion 73 fast on a cam shaft 74 journaled in the machine frame 15 and provided with a cam 75 having a groove 76 in which operates a roller 77 carried by the lower arm of the bell-crank lever 66. As the cam 75 is rotated the lever 66 is oscillated on its pivot, thereby causing the outer end of the shaft 55 with the forming roller 56 to be raised and lowered. The form of the cam groove 76 is such as to cause a vertical movement of the roller 56 just sufficient to compensate for the vertical component of the movement of the chucks 31 due to the rotation of the spool 24, so that said roller 56 is held in engagement with the upper sides of the forms held by said chucks during a considerable arc of their movement, as will be clear by a comparison of Figs. 2 and 5^a. The limits of the vertical movement of the forming roller may be varied in accordance 50 with the character of the work, and particularly the size of forms used, by adjusting the extension 65 upon its pivot 69. It will be observed that the flexible shaft section 54 not only permits the movements last referred to, but also permits the angular ad-

justment of the arm 60 as heretofore described.

The operation of the machine is as follows: The bodies of the nipples or other articles are molded on the forms 36 and 360 70 in any usual or well known way, as by dipping, leaving rough or unfinished edges 78 or 780 at the open mouths of said articles, as indicated in Figs. 4 and 9. Power having been applied to the machine, the spool or form carrier 24 is rotated in the direction of the arrows on Figs. 1 and 2. As the heads 34 on the operating rods 33 are brought into engagement with the cam plate 37, the chucks are opened or released, 75 permitting the forms to be applied thereto, which forms are subsequently clamped to the chucks as the heads 34 move out of engagement with said cam plate. It will be understood that the operator, as the several chucks are brought to the lowermost point of their travel, successively replaces the forms which have been carried past the forming roller with fresh forms containing nipples or other articles to be operated upon. As the chucks pass out of engagement with the cam plate 37, causing the forms to be securely clamped in place thereon, the pulleys 48 on said chucks are brought into engagement with the belt 50, 90 causing said chucks and forms to be rotated in the direction of the arrows in Figs. 1 and 2. As each form, while being so rotated, is brought into engagement with the forming roller 56, the rough edge 78 of the nipple or other article thereon is engaged by said roller, said form remaining in engagement with said roller during its travel through the upper arc of its movement, and moving longitudinally of said roller. The direction of movement of that face of the forming roller in engagement with the form being outward or toward the body of the nipple or other article thereon, and the direction of movement of that face of the form in engagement with the roller being in the direction of travel of said form, the action of the roller is to turn the rough edge 78 outwardly or forwardly, causing the same to roll upon itself and form the desired roll or bead, this action being aided by the inclination of the roller 56, by reason of which it will be seen that the combined movements of the form and roller in engagement are toward, or in opposition to one another, so as to cause the edge 78 to roll up in the manner stated. This operation takes place while the material of the nipple or other article is still in a plastic or unvulcanized condition so that said material adheres to itself as soon as rolled up, forming a solid mass. As each form 36 travels longitudinally of the roller 56 the point of engagement of said form and roller, by reason of the outward inclination of the roller, moves 110 115 120 125 130

outwardly of the form, causing said roller to follow the bead outwardly as it is reformed.

Having thus described my invention I claim and desire to secure by Letters Patent:

1. A machine of the character described comprising, in combination, a traveling and rotating form, a shaft, a rotatable actuator for said shaft, a section of flexible shafting 10 connecting one end of said shaft with said actuator, means for adjustably supporting the opposite end of said shaft to hold the same at a variable angle to the direction of travel of said form, and a forming roller on 15 said shaft and engaging said form.

2. A machine of the character described comprising, in combination, a traveling and rotating form, a rotating forming roller engaging said form, a pivoted arm extending 20 longitudinally of said roller for supporting the same at an angle to the direction of travel of said form, and means for clamping said arm in adjusted position.

3. A machine of the character described 25 comprising, in combination, a traveling and rotating form, a shaft, a rotatable actuator for said shaft, a section of flexible shafting connecting one end of said shaft with said actuator, a pivoted arm extending longitudinally of said shaft for adjustably supporting the opposite end thereof to hold the same at a variable angle to the direction of travel of said form, means for clamping said arm in adjusted position, and a forming roller on 30 35 said shaft and engaging said form.

4. A machine of the character described comprising, in combination, a plurality of 40 chucks, forms carried by said chucks, bead forming means, means for relatively moving said chucks and bead forming means to move said forms successively into operative relationship to said bead forming means, and means for automatically operating said chucks to clamp said forms when in operative relationship to said bead forming 45 means and to release the same after passing out of operative relationship therewith.

5. A machine of the character described comprising, in combination, a plurality of 50 chucks, forms carried by said chucks, bead forming means, means for relatively moving said chucks and bead forming means to move said forms successively into operative relationship to said bead forming means, a cam 55 plate, and means carried by said chucks and engaged and disengaged by said cam plate for operating said chucks to clamp and release said forms.

6. A machine of the character described 60 comprising, in combination, a plurality of chucks, forms carried by said chucks, a forming roller, means for relatively moving said chucks and roller to move said forms successively into engagement with said roller, a cam plate, longitudinally sliding rods car-

ried by said chucks and provided with means for operating said chucks to clamp and release said forms, and springs for moving said rods to operate said chucks to clamp said forms, said rods having heads engaged and moved by said cam plate to operate said chucks to release said forms.

7. A machine of the character described comprising, in combination, a form carrier, a plurality of chucks in said carrier, forms 75 carried by said chucks, a forming roller, means for moving said form carrier to bring said forms successively into engagement with said roller, and means for automatically operating said chucks to clamp said forms 80 when in engagement with said roller and to release the same after passing out of engagement with said roller.

8. A machine of the character described comprising, in combination, a plurality of 85 forms, a form carrier, a forming roller, means for moving said form carrier to bring said forms successively into engagement with said roller, and means independent of said carrying and moving means for rotating 90 said forms in said carrier.

9. A machine of the character described comprising, in combination, a rotating form carrier, a plurality of chucks in said carrier, forms carried by said chucks, a forming roller, said forms being successively brought into engagement with said roller as said carrier is rotated, a cam plate having a cam edge arranged substantially in the plane of the axis of rotation of said carrier, and means carried by said chucks and brought into and out of engagement with said cam plate to operate said chucks to clamp and release said forms.

10. A machine of the character described comprising, in combination, a rotary form carrier having a pair of annular flanges, bushings in said flanges, a plurality of chucks rotatably mounted in said bushings, forms carried by said chucks, means for rotating said chucks in said bushings, a forming roller, and means for rotating said form carrier to bring said forms successively into engagement with said roller.

11. A machine of the character described comprising, in combination, a rotary form carrier, a plurality of chucks journaled in said carrier, forms carried by said chucks, a forming roller, means for rotating said form carrier to bring said forms successively into engagement with said roller, pulleys carried by said chucks, and a belt engaged by said pulleys successively as the corresponding chucks are brought into engagement with said roller.

12. A machine of the character described comprising, in combination, a rotary form carrier having a pair of annular flanges, bushings in said flanges, a plurality of chucks rotatably mounted in said bushings,

- forms carried by said chucks, a forming roller, means for rotating said form carrier to bring said forms successively into engagement with said roller, pulleys carried by 5 said chucks between said bushings, and a belt engaged by said pulleys successively as the corresponding chucks are brought into engagement with said roller.
13. A machine of the character described comprising, in combination, a plurality of forms, a rotating form carrier, a forming roller, means for rotating said form carrier to move said forms successively into engagement with said roller and move the 10 same relative to said roller while in engagement therewith, and means for bodily moving said roller to hold the same in engagement with said forms.
14. A machine of the character described comprising, in combination, a plurality of forms, a rotating form carrier, a forming roller, means for rotating said form carrier to move said forms successively into engagement with said roller and move the 15 same relative to said roller while in engagement therewith, and means for adjustably securing said roller at an angle to the direction of travel of said forms, and means for bodily moving said roller to hold the same in engagement with said forms.
15. A machine of the character described comprising, in combination, a plurality of forms, a rotating form carrier, a forming roller, means for rotating said form carrier to move said forms successively into engagement with said roller and move the same relative to said roller while in engagement therewith, a shaft on which said roller is 20 mounted, a bearing for said shaft, a supporting arm having a slotted end in which said bearing is movably mounted, and means for moving said bearing to hold said roller in engagement with said forms.
16. A machine of the character described comprising, in combination, a rotating form carrier, a plurality of rotating forms in said carrier, a rotating forming roller, means for rotating said form carrier to move said forms successively into engagement 25 with said roller and move the same relative to said roller while in engagement therewith, a shaft on which said roller is mounted, a bearing for said shaft, a pivoted supporting arm having a slotted end in which said bearing is movably mounted for holding 30 said shaft and roller at an angle to the direction of movement of said forms, means for clamping said arm in adjusted position, and means for moving said bearing in said slotted end for holding said roller in engagement with said forms.
17. A machine of the character described comprising, in combination, a plurality of forms, a rotating form carrier, a forming roller, means for rotating said form carrier to move said forms successively into engagement with said roller and move the same 35

- carrier to move said forms successively into engagement with said roller and move the same relative to said roller while in engagement therewith, a shaft on which said roller is mounted, and a lever coöperating with said shaft for moving said roller to hold the same in engagement with said forms.
18. A machine of the character described comprising, in combination, a plurality of forms, a rotating form carrier, a forming roller, means for rotating said form carrier to move said forms successively into engagement with said roller and move the same relative to said roller while in engagement therewith, a shaft on which said roller is mounted, a bearing for said shaft, a lever having a slotted end in which said bearing is received, and means for operating said lever to move said roller and hold the same in engagement with said forms.
19. A machine of the character described comprising, in combination, a plurality of forms, a rotating form carrier, a forming roller, means for rotating said form carrier to move said forms successively into engagement with said roller and move the same relative to said roller while in engagement therewith, a shaft on which said roller is mounted, bearings for the end of said shaft, a supporting arm having a slotted end in which one of said bearings is movably mounted, a lever having a slotted end in which the other of said bearings is received, and means for operating said lever to move said roller and hold the same in engagement with said forms.
20. A machine of the character described comprising, in combination, a rotating form carrier, a plurality of rotating forms in said carrier, a shaft, means for rotating said shaft, a flexible connection between one end of said shaft and said rotating means, a forming roller on said shaft, means for rotating said form carrier to move said forms successively into and out of engagement with said roller and move the same relative to said roller while in engagement therewith, bearings for the end of said shaft opposite said flexible connection, a pivoted arm having a slotted end in which one of said bearings is movably mounted for holding said roller at a variable angle to the direction of travel of said forms, means for clamping said arm in adjusted position, a lever having a slotted end in which the other of said bearings is received, and means for operating said lever to move said roller and hold the same in engagement with said forms.
21. A machine of the character described comprising, in combination, a plurality of forms, a rotating form carrier, a forming roller, means for rotating said form carrier to move said forms successively into engagement with said roller and move the same

- 6
 relative to said roller while in engagement therewith, a shaft on which said roller is mounted, and a lever coöperating with said shaft for moving said roller to hold the same in engagement with said forms, said parts having provision for adjusting the movement imparted to said shaft by said lever. 22. A machine of the character described comprising, in combination, a plurality of forms, a rotating form carrier, a forming roller, means for rotating said form carrier to move said forms successively into engagement with said roller and move the same relative to said roller while in engagement therewith, a shaft on which said roller is mounted, and a lever having a pivoted adjustable extension coöperating with said shaft for moving said roller to hold the same in engagement with said forms. 23. A machine of the character described comprising, in combination, a plurality of forms, a rotating form carrier, a forming roller, means for rotating said form carrier to move said forms successively into engagement with said roller and move the same relative to said roller while in engagement therewith, a shaft on which said roller is mounted, a bearing for said shaft, a lever having a pivoted adjustable extension provided with a slotted end in which said bearing is received, and means for operating said lever to move said roller and hold the same in engagement with said forms. 24. A machine of the character described comprising, in combination, a plurality of forms, a rotating form carrier, a forming roller, means for rotating said form carrier to move said forms successively into engagement with said roller and move the same relative to said roller while in engagement therewith, a shaft on which said roller is mounted, a lever coöperating with said shaft for moving said roller to hold the same in engagement with said forms, and a cam for operating said lever. 25. A machine of the character described comprising, in combination, a plurality of forms, a rotating form carrier having an annular flange in which said forms are journaled, a forming roller, means for rotating said form carrier to move said forms successively into engagement with said roller and move the same relative to said roller while in engagement therewith, a shaft on which said roller is mounted, a lever coöperating with said shaft for moving said roller to hold the same in engagement with said forms, a cam to operate said lever, a shaft on which said cam is mounted, a pinion on said cam shaft, and a gear on the flange of said form carrier meshing with said pinion. 26. A machine of the character described comprising, in combination, a rotary form carrier having a pair of annular flanges, bushings in said flanges, a plurality of chucks rotatably mounted in said bushings, forms carried by said chucks, means for rotating said chucks in said bushings, a forming roller, means for rotating said form carrier to move said forms successively into engagement with said roller and move the same relative to said roller while in engagement therewith, a shaft on which said roller is mounted, a lever coöperating with said shaft for moving said roller to hold the same in engagement with said forms; a cam to operate said lever, a shaft on which said cam is mounted, a pinion on said cam shaft, and a gear on one of the flanges of said form carrier meshing with said pinion. 27. A machine of the character described comprising, in combination, a plurality of chucks, forms carried by said chucks, a form carrier in which said chucks are rotatably mounted, means for rotating said chucks, a forming roller, means for moving said form carrier to bring said forms successively into engagement with said roller and to bring said chucks successively into engagement with said rotating means, and means for automatically operating said chucks to clamp said forms when said chucks and forms are in engagement with said roller and rotating means, respectively, and subsequently to release the same. 28. A machine of the character described comprising, in combination, a rotary form carrier, a plurality of chucks journaled in said carrier, forms carried by said chucks, a forming roller, means for rotating said form carrier to bring said forms successively into engagement with said roller, pulleys secured to said chucks, a belt engaged by said pulleys successively as the corresponding chucks are brought into engagement with said roller, a cam plate, and means carried by said chucks and brought into and out of engagement with said cam plate for operating said chucks to clamp and release said forms. In testimony whereof I affix my signature in presence of two witnesses. JEREMIAH L. MAHONEY. Witnesses: EDWIN S. PICKETT, JACOB E. BLATCHLEY.
